DESIGN FOR A TEXTILE FABRIC

Ruth Hilf, Croton on Hudson, N. Y., assignor to Bernard Bernstein Textile Co., New York, N. Y., a corporation of New York

Application April 11, 1938, Serial No. 76,437

Term of patent 3½ years

To all whom it may concern:

Be it known that I, Ruth Hilf, a citizen of the United States, residing at Croton on Hudson, county of Westchester, State of New York, have invented a new, original, and ornamental Design for a Textile Fabric, of which the following is a specification, reference being had to the accompanying drawing, forming part thereof.

The figure is a plan view of a textile fabric showing my new design.

I claim:

The ornamental design for a textile fabric, as shown.

RUTH HILF.
